DESIGN FOR A DRESS

Natalie Renke, New York, N. Y.

Application July 31, 1941, Serial No. 102,588

Term of patent 3½ years

To all whom it may concern:

Be it known that I, Natalie Renke, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design, and

Fig. 2 is the rear view thereof.

The characteristic feature of my design resides in the specific two-piece, full-skirted shirt-waist dress disclosed having a wide belted skirt in association with a contrasting blouse member, said skirt member being edged around the bottom with a comparatively narrow band matching the blouse member, all as shown.

I claim:

The ornamental design for a dress, substantially as shown and described.

NATALIE RENKE.
